C. F. JENKINS

OFF-SET FILAMENT LAMP

Filed Oct. 22, 1924

C. Francis Jenkins Inventor

UNITED STATES PATENT OFFICE.

CHARLES FRANCIS JENKINS, OF WASHINGTON, DISTRICT OF COLUMBIA.

OFFSET FILAMENT LAMP.

Application filed October 22, 1924. Serial No. 745,212.

To all whom it may concern:

Be it known that I, CHARLES FRANCIS JENKINS, citizen of the United States, residing at Washington, District of Columbia, ⁵ have invented certain new and useful Improvements in Offset Filament Lamps, of which the following is a specification.

This invention relates to devices for use in the transmission of photographs by radio, ¹⁰ and for other purposes, and has for its principal object to provide a light source without the objections of other sources.

With this and other objects in view the invention consists in the novel details of ¹⁵ construction and combination of parts more fully hereinafter disclosed and particularly pointed out in the claims.

Referring to the accompanying drawings forming a part of this specification, in which ²⁰ like symbols refer to like parts in both views—

Fig. 1 is a diagrammatic drawing of a usual arrangement, and Fig. 2 the novel arrangement of applicant's invention, in both ²⁵ of which—

A is a filament lamp; B an apertured diaphragm; C a lens; D a light receiving surface, and α' the filament of the lamp.

In Fig. 1 the filament of the lamp is located in the usual place, i. e., in the centre of the lamp. In Fig. 2 the filament is located almost touching the glass wall of the lamp.

In certain work, for example, the transmission of photographs, it is desirable to have a mask with a very small aperture therein in front of the source of light, in this case a small coil of very fine filament wire. When the aperture is small enough

to be effective, say, one-hundredth inch in ⁴⁰ diameter, this minute opening acts as a "pin-hole" camera forming a large size image of the filament, on the same picture screen (D) that the lens C does, and with a consequent confusion destructive of acceptable results. ⁴⁵

However, by moving the filament over near to or touching the glass wall the "pin-hole" effect is avoided, and a single sharp image on the screen results.

Filling the lamp with hydrogen so distributes the heat of the filament on the adjacent area of glass that the glass does not crack.

It is obvious to those skilled in the art that the light source need not be limited ⁵⁵ to a filament, nor that the enclosing casing need necessarily be filled with hydrogen under all circumstances.

What I claim, is—

1. In a lamp unit, a light source, an enclosing casing therefor filled with hydrogen, ⁶⁰ said light source located in approximate contact with the casing wall.

2. In a lamp unit, a light source, and an enclosing casing, said light source being located in approximate contact with said casing wall. ⁶⁵

3. In a lamp unit, a filament light source, and an enclosing casing, said filament being located in approximate contact with the casing wall. ⁷⁰

4. In a lamp unit, a filament light source, and an enclosing casing filled with hydrogen, ⁷⁵ said filament being located in approximate contact with the casing wall.

In testimony whereof I have affixed my signature.

CHARLES FRANCIS JENKINS.
